Application October 10, 1955, Serial No. 539,464

9 Claims. (Cl. 72—46)

This invention relates to readily assembled, demountable, self-contained, non-load-bearing, dry-wall partition construction and is particularly directed to arrangements and combinations of components of novel characteristics whereby non-load-bearing partitions may be erected in homes, office building, municipal building, schools and the like, in an extremely rapid and effective manner.

Partition walls in various buildings have heretofore been made of gypsum blocks or involve the use of studs, lath and plaster. Certain partitions in office buildings and the like have been made of a relatively light metallic framework and panels of glass, but such lightweight office partitions do not conform to the requirements of fireproofing or fire resistance which are ordinarily enforced in most structures. It may be noted that partitions offering a certain minimum resistance to the passage of heat or fire involve plastering or the application of stucco and plaster, and the erection of such partitions is both expensive and time-consuming. Moreover, normal methods of constructing non-load-bearing partitions make it difficult to properly place and conduct electrical conduits, telephone lines, lines conveying gas, compressed air, water, or other necessary materials (as in buildings devoted to medical offices, etc.).

Generally stated, the present invention contemplates a system of building non-load-bearing partitions which eliminates the necessity of applying stucco or plaster, the method of construction being generally referred to as dry-wall construction. The system contemplated by the present invention employs an adjustable floor runner which may be readily connected or attached to any type of floor, the floor runner being laterally adjustable so as to permit such runner to firmly support, anchor and grasp a dry-wall partition of any desired thickness. It is to be understood that partitions may vary in thickness depending upon structural or architectural considerations and the use to which the building is put.

Again, the present invention contemplates an adjustable floor runner which not only telescopes laterally and is therefore adjustable to partitions of different widths, but also provides a housing adapted to readily receive telephone and electric lines, conduits, heating elements or the like. The floor runner is provided with removable mop or base kick plates which impart a finished appearance to the partition and effectively conceal the wires or piping extending therethrough.

Moreover, the present invention contemplates the use of a novel ceiling runner which readily receives prefabricated panels, anchors the same and permits the application of external, surface panels to the core and ceiling runner. The mode of construction therefore permits the application of external surface panels of any desired type, color, texture or finish.

It is an object of the present invention, therefore, to disclose and provide a novel system of constructing demountable, self-contained, non-load-bearing partitions.

A further object of the invention is to disclose and provide a method of construction and elements for use

2

therein whereby non-load-bearing partitions made from laminated panels of different thicknesses may be readily installed and be caused to contain readily accessible wiring, conduits and the like.

5 A further object of the invention is to disclose and provide a new floor runner adapted to positively support and anchor non-load-bearing partitions, such floor runner being adjustable to partitions of differing thicknesses.

An object of the present invention is to provide a novel 10 and improved ceiling runner adapted to receive and firmly hold the upper edges of a laminated core of a partition wall and to be concealed by externally applied surface panels.

Moreover, it is an object of the present invention to 15 disclose and provide a demountable, self-contained, readily assembled, non-load-bearing partition construction, said partition being composed of a core consisting of a plurality of panels adhesively secured together in face-to-face relation, such core having exterior surface panels adhesively secured to the core.

These and various other objects, uses, and advantages of 20 the present invention will be more readily understood and appreciated from the description given hereinafter of certain exemplary forms of construction and elements 25 for use therein. In order to facilitate description and understanding, reference will be had to the appended drawings, in which:

Fig. 1 illustrates transverse sections taken through portions of various types A, B, C, D of partitions which may 30 be employed.

Figs. 2, 3, 4, 5 and 6 illustrate a sequence of steps employed in assembling and erecting a non-load-bearing partition in accordance with the present invention.

Fig. 7 is an enlarged, vertical section and isometric of 35 a base runner and cooperating ceiling runner, the partition panel and ceiling finish being indicated in dash lines.

Fig. 8 is a horizontal section through partition walls 40 formed in accordance with the present invention in a zone where one partition abuts and terminates at a transverse partition.

Fig. 9 is a horizontal section illustrating an arrangement of partition walls meeting at a corner.

Fig. 10 is an isometric view of a removable base plate 45 adapted for use on inside corners.

Fig. 11 is an isometric view of a removable base plate adapted for use on outside corners.

Fig. 12 is a vertical section through a slightly modified form of floor runner.

50 Fig. 13 is a horizontal section through an adjustable metallic door frame adapted for use with partitions of this invention.

The partitions of the present invention may be made of 55 various thicknesses by the use of gypsum boards or the like of individual thickness ranging from $\frac{1}{4}$ " to 1". Fig. 1 illustrates a series of partial sections through partitions composed of various gypsum boards. Section A, for example, comprises a central core made of two gypsum boards 1 and 1' which have been adhesively secured together by their contacting faces prior to installation in the wall. Such core is then provided with external or surface panels such as the gypsum board panels 2 and 2' adhesively secured to the external surfaces of the core. This section A is shown made of four boards of equal thickness. If each of these boards or panels is $\frac{5}{8}$ " thick, the total thickness of the partition is $2\frac{1}{2}$ ".

Section B illustrates a thinner partition wherein the core 60 is composed of two adhesively secured gypsum boards, the surfacing panels indicated at 4 and 4' being adhesively secured to the exterior surfaces of the core. These external or surfacing panels may be quarter inch plywood, fiberboard, sound absorbing tile or any other desired ma-

terial and may be of appreciably thinner section than those utilized in section A.

The section indicated at C illustrates a core 3' composed of two thicker gypsum panels or the like provided with external or surfacing panels 5 and 5' which may also be gypsum board of any desired type and of any desired thickness. Section D illustrates a modified wall partition wherein the core 3'' is composed of three panels adhesively secured together into a unit, one external surface panel 6' being thicker than the other external surface panel 6. It will be evident from a contemplation of the various typical sections A, B, C and D that wall partitions of a variety of thicknesses may be made, the materials employed being compatible to the rooms and functions to be performed, the finish desired, etc. The fire resistance rating of these partitions may also be varied in order to conform with building requirements.

By referring to Figs. 2, 3, 4, 5 and 6, the sequence of steps employed in assembling and erecting a non-load-bearing partition in accordance with the present invention will be readily understood. The first step comprises attaching a ceiling runner, generally indicated at 10, to the ceiling in axial alignment with one portion of a longitudinally extending laterally telescoping floor runner. This portion of the floor runner is indicated at 11' and is fastened to the floor by means of cement nails, rivets or the like which are driven through the portion 12 of the foot plate. It may be noted that the ceiling runner is either provided with downwardly extending stop tabs such as 10' or such tabs are bent out of the ceiling runner, the tabs being in vertical alignment with the vertical web of member 11' of the floor runner.

Fig. 3 illustrates the step of placing a core 3 upon the foot plate of member 11', the weight of such core resting upon the foot plate, the side of the core pressing against the vertical web of member 11' and the upper edge portion of such core resting against the downwardly extending stop tabs 10' of the ceiling runner. After the core has been raised in this position it is retained in such position by bending down an additional tab or tabs such as 10" from the ceiling runner into contact with the outer surface of the core. It may be mentioned at this time that the core is composed of two or more panels adhesively secured together in face to face relation, thus forming a rigid element which may be from 1 to 3 feet in width.

Fig. 4 illustrates a further step in the erection of a partition in accordance with this invention. As there shown the telescoping member 11" of the floor runner is attached to the foot plate of member 11' in any suitable manner as, for example, by permitting the upstanding stud to extend through a slot in the bottom portion of member 11" and applying a nut to the end of the stud. It will be noted that by the placement and attachment of the member 11" the lower section of the core 3 is grasped by the members 11' and 11" and maintained in fixed position.

Fig. 5 illustrates subsequent steps wherein external panels such as the panels 2 and 2' are adhesively secured to the external surfaces of the core 3, which is now firmly anchored to the ceiling runner and to the floor runner.

Fig. 6 illustrates the final steps in the erection of a panel, such final steps comprising the application of kick plates 20 and 20' to upstanding flanges on the outer margins of members 11' and 11", such kick plates preferably including electrical outlets and cooperating with the floor runner to provide readily accessible passageways in which telephone lines, air lines, water lines, etc., may be placed.

Fig. 7 shows in greater detail the construction of the ceiling runner and the floor runner. As there shown, the ceiling runner 10 is of substantially that section and is provided with outwardly extending upper flanges 14 and 14' which may be provided with spaced perforations to facilitate the attachment or anchoring of a ceiling runner to a ceiling, joists, beams or the like. The two opposing

side walls of the ceiling runner are preferably lanced so as to provide anchor tabs such as 10', these anchor tabs being bent outwardly and downwardly from the side walls of the ceiling runner.

5 The telescoping and adjustable floor runner, generally indicated by the numeral 11, comprises the two sections 11' and 11", the first of these having a foot plate 15 extending laterally in each direction from the vertical web 16. The portion 12 of the foot plate 15 may be perforated at intervals to facilitate the nailing or anchoring of the member 11' to the floor. It will be noticed that the member 11' is also provided with a top plate 17 provided with an upstanding flange 18. The portion 12 of the foot plate is also provided with an upstanding flange 19, the flange 19 being preferably further removed from the vertical web 16 than the top flange 18. Attention is called also to the fact that, as well shown in Fig. 7, the weight of the core 3 rests directly upon the foot plate 15 of the member 11'.

20 The foot plate 15 is provided with an upstanding threaded stud such as 25 at spaced longitudinal intervals. These studs 25 extend through spaced laterally extending slots formed in the bottom of plate 27 of member 11', which includes the angle web 28 and a top plate 29, said top plate being provided with an upstanding flange 30. When the member 11' is applied to the foot plate 15 of member 11', the studs 25 extend through the slots and the member 11' is anchored and connected to member 11' by means of nuts 26. Foot plate 27 of member 11' is also provided with an upstanding flange 31.

It will be noted that the top plates 17 and 29 are sufficiently wide to accommodate the subsequently applied surface panels such as 2 and 2' and leave a space between the flanges (18 and 30) and the external surfaces 35 of these surfacing panels 2 and 2'.

These various flanges 18, 19, 30 and 31 provide means which cooperate with the kick plates 20 and 20'. The kick plate 20 may be provided with an upper portion including a reentrant curved lip 32 adapted to grasp flange 40 30 and extend into the space between the inner surface of such flange and the outer surface of facing board or panel 2. The bottom portion of kick plate 20 may be provided with an upstanding rib having a downwardly extending lip 33 adapted to grasp flange 31. The main portion of kick plate 20 may be lanced or perforated at intervals, each of the ports or perforations grasping an outlet plug 35. These outlet plugs may be suitably spaced longitudinally of the kick plate and be interconnected by means of supply and ground wires leading to a source of electrical energy and to ground, respectively. These wires 50 may be contained in a light-weight snap-on conduit, one portion of the conduit such as 36 being spot welded to the inner surface of the kick plate 20 whereas the outer portion 36' is removably attached to the first portion 36. 55 These various kick plates, together with their outlet plugs and interconnecting wiring, may be prefabricated, thereby greatly facilitating wiring required in rooms formed by the partition.

It may be noted at this time that when the surfacing panels such as 2 and 2' are adhesively secured to the core 3, the vertical edges of the surface panels 2 and 2' extend beyond the vertical edges of the cores 3 on one side and the edge of the core extending beyond the vertical edge of the panels on the other side. In this manner broken joints are provided in the partition, imparting greater strength to the entire assembly. If desired, the vertical edges of the surface panels 2 and 2' may be rounded or grooved, imparting an attractive vertical paneling effect to the rooms provided with these partitions. In the event the partition cores and surface panels are 18"-36" in width, they may be easily and readily handled either during erection of the partition or during any subsequent disassembly or salvaging operation.

A partition constructed in accordance with the process of the invention noted above has remarkable strength

and rigidity and high fire resistance rating. It will be noted that the only metal-to-metal contact exists on the floor between the foot plates of members 11' and 11", the core acting as an insulator between such members. Furthermore, it will be noted that the thickness of the core can be varied, member 11" being in telescoping relation with member 11', adjustment being permitted by the cooperation of the threaded stud 25 with the laterally elongated slot in the foot plate 27 of member 11'. When sound absorbing ceiling panels are used as indicated at 38, the thickness of such ceiling panels adequately covers any unevenness between the top of the external surfacing panels and the ceiling, thereby permitting a clean smooth finish to be obtained.

It is understood that the floor runner may be either made of extruded metal or of sheet metal. The kick plates 20 and 20' are also preferably made of sheet metal although they can be made of a plastic composition if so desired.

Fig. 8 illustrates one manner in which panels can intersect. As there shown a partition wall including core 3 abuts another partition including core 3'. Surface panels 2 and 2' are applied to core 3, one edge of such surface panels terminating at 42 and the other being flush with core 3'. Additional surface panels such as 43 and 44 are then applied to the core 3', one vertical edge of each of said panels being in abutting relation to the surface panels 2 and 2'. Opposite vertical edges of the panels 43 and 44 are caused to be spaced from edges 45 and 46 of the core 3' to give rise to the tongue and groove or overlapping at the joists.

Fig. 9 illustrates a corner construction wherein the external surface panels such as 2 and 2" encase the external corner and meet at a beveled edge 47. External corners of these non-load-bearing partitions may be additionally protected by means of a vertically extending metal channel 48 suitably secured to such corner. In some instances such external corners may be vertically reinforced by adhesively applied fibrous tape, particularly when the external surfaces are finished with paint or other similar coating.

The various kick plates on the partitions may be joined at internal and external corners by means of prefabricated corner elements such as are illustrated in Figs. 10 and 11.

It is to be understood that the floor runner (as well as ceiling anchors) are made of any desired length and are normally provided with transverse ends. When partitions meet at a corner, these floor runners may either be cut to provide a tapered or beveled end or preferably and simply are left with transverse ends and stop where the inner portions of the corner would meet. In order to breach the gap and give corners a finished appearance at the base plate, preformed, one-piece, inside and outside corner elements for the base plates or kick plates are provided, as illustrated in Figs. 10 and 11.

Fig. 10 illustrates a one-piece inside corner base plate 50 of the same cross section as the remaining or linear portions of the base plate, said inside corner being composed of two portions 51 and 52 welded or otherwise attached together as at 53. This entire corner element may be simply installed and caused to abut the ends of adjacent linear base plates. In some instances it is desirable to employ a short section of a base plate splice such as is indicated at 54, this splice being made slightly smaller than the base plate so as to be slidably received in the end of a base plate and interconnect adjacent lengths of base plate or interconnect a corner element such as 50 with the adjoining linear base plate.

Fig. 11 illustrates a similar one-piece outside corner element 50' similarly made of portions 51' and 52' welded or brazed together at a 45° joint 53'.

It may be mentioned at this time that the term "adhesively secured" as used herein refers to panels which have been connected together by means of a resin, rubber or silicate base cement, glue, or any other desired type of

adhesive. As previously indicated, the cores 3 comprise adhesively secured panels which have been glued or combined prior to erection. The external surfacing panels such as 2 and 2' are then glued onto the vertical, external surfaces of the core.

The telescoping type of floor runner may vary in details from that illustrated most specifically in Fig. 7. Fig. 12 illustrates a modified form of floor runner. In the form illustrated in Fig. 12 both the core and the external surfacing panels rest upon the upper portions of the floor runner.

The floor runner illustrated in Fig. 12 comprises a member generally identified as 57 having a longitudinally extending, vertical web, a horizontal foot plate 58 extending laterally in both directions from the web and a top plate 59 extending laterally in one direction only. The top plate 59 is provided with an upstanding flange 60; the foot plate is provided with the upstanding flange 60' which may be in vertical alignment with flange 60 or extend somewhat therewith, being further spaced from the vertical web of member 57.

This floor runner member 57 is first firmly anchored to a floor as by cement nails or anchor pins 61 driven through the outwardly extending portion of the foot plate 58. Thereafter, the floor runner member 63 is connected to the member 57. The member 63 also includes a vertical web and a foot plate 64 extending in one lateral direction, the top plate 65 extending in both lateral directions. The foot plate is adapted to rest upon foot plate 58 whereas the top plate 65 is adapted to rest upon top plate 59. The foot plate 64 is provided with an upstanding flange 66 and the top plate 65 is provided with the upstanding flange 66'. It may be noted that the vertical, upstanding flanges 60 and 66' are spaced from their respective webs a distance about one-half the minimum partition thickness to be supported by the floor runner. Since the partition to be supported may vary in thickness, the webs of members 57 and 63 are spaced a predetermined and variable distance so as to eventually cause the flanges 60 and 66' to firmly anchor the partition and restrain it from lateral movement. The vertical webs of members 57 and 63 are provided with longitudinally spaced and preferably vertically staggered ports. The members 57 and 63 are then connected together by means of a bolt, such as the bolt 67, extending through aligned ports in the vertical webs, a cylindrical spacer 68 being applied to the shank of the bolt and between the webs of members 57 and 63 so as to establish a predetermined space. Nuts, such as 69, are then applied for the purpose of holding the assembly in the desired position.

The form of floor runner here illustrated presents an upper surface upon which both the core and the external surfacing panels are permitted to rest between the flanges 60 and 66'. In the event it is desired to impart greater heat insulating properties to such floor runner, the top plate 65 of members 63 may be provided with spaced apertures such as 70. After the floor runner has been assembled, as previously stated, heat insulating material (such as a porous, gypsum composition, granulated or finely divided insulating inorganic powders, mineral wool, or the like) may be introduced through the apertures 70, completely filling the space between the vertical webs of members 57 and 63.

It will be noted that the foot plate 64 of member 63 extends beyond the lateral extension of foot plate 58, unless the vertical webs of members 57 and 63 are in contact, and a very thin partition is being supported. In the event foot plate 64 extends materially beyond foot plate 58, shims are introduced therebeneath. In some instances, particularly where the upstanding flanges 60' and 66 are spaced a greater distance from their respective vertical webs than the upper flanges, a downwardly extending bead may be formed integrally with foot plate 64 immediately below the flange 66, thereby obviating the necessity of employing shims.

The construction herein disclosed is particularly well adapted for use with adjustable, two-piece metal door frames. The laminated gypsum board partitions may be readily trimmed, openings left therein wherever desired, and telescoping door jambs rapidly placed within door openings; the door jamb sections embracing edge areas of the partition to provide a hollow door frame provided with an integral door stop. Such hollow, telescoping door frames permit electrical wiring to be rapidly and easily threaded from one base plate area on one side of the door to the base plate area on the other side of the door. A typical jamb section through such adjustable metal door frame is illustrated in Fig. 13. As there shown, the partition 75 (composed of preformed, precombined core and subsequently applied surfacing panels) terminates at a vertical end 76, constituting a part of the roughed-in door opening. The adjustable door frame is composed of two sections, one of them indicated at 77 and the other indicated at 78, adapted to telescopically engage, the portion 78 including a preformed door stop 79. It will be noted that each of these door jamb frames includes an external face and an internal reentrant flange portion, such as 77 and 78, adapted to bear against the external surfaces of the partition. The entire door frame is then connected to the partition as by means of the companion screw elements 80 extending through the partition. A machine screw 81 extends through the door stop 79 and connects that portion of frame 78 with the underlying portion of frame 77. The hollow space thus formed around the end of the partition 75 provides a suitable runway for electrical connections, telephone lines, etc.

The core assembly may be made of any desired type of fabricated boards, such as gypsum composition, balsa fiber, wood fiber, laminated wood, etc., or combinations thereof. Partitions of type D (Fig. 1) may well include a core of three inches composed of two gypsum boards with an intervening loose-textured balsa fiber board, such core being rigid, strong, readily handled and erected, and at the same time capable of imparting greater sound-insulating properties to the finished partition than gypsum boards alone. The invention permits flexibility and the construction of different types of partitions of different thicknesses, surface finishes, fire-resistance ratings, thermal and sound transmission characteristics, etc., from standardized materials and elements, in an inexpensive and rapid manner, for various and different requirements.

It is to be understood that the enclosed conduit 36-36' with its outlet plugs need not be used as illustrated. The kick plate 20 may be preformed with a longitudinally extending recess adapted to removably receive the conduit element 36 with its outlet plugs and interconnecting wires, the outer face of such element 36 then lying in the same plane as the outer face of the kick plate. All changes and modifications coming within the scope of the appended claims are embraced thereby.

We claim:

1. A readily erected, non-load-bearing partition construction comprising: a ceiling anchor runner connected to a ceiling; an adjustable floor runner on a floor in alignment with the ceiling runner and having means for receiving varying thicknesses of partition walls; core panels each composed of two or more gypsum boards adhesively secured in face-to-face relation extending from substantially the floor to said ceiling runner and connected to said ceiling runner against lateral movement, the lower portions of said core panels being grasped by the floor runner, vertical edges of said core panels being coplanar, and surfacing panels adhesively secured to external surfaces of said core panels, upper edge portions of said surfacing panels extending above the tops of said core panels and enclosing the ceiling anchor runner, vertical edges of said surfacing panels being displaced with respect to the vertical edges of said core panels, the lower edges of said surfacing panels termi-

nating above the lower edges of the core panels and supported by said floor runner.

2. A partition construction as stated in claim 1, wherein the floor runner is provided with outwardly directed top plates spaced from the floor and supporting said surfacing panels.

3. A partition construction as stated in claim 1, wherein the floor runner is provided with outwardly directed top plates spaced from the floor and supporting said surfacing panels, and an upstanding flange carried by each of said top plates, said flanges restraining said surfacing panels from lateral motion, and a removable base plate in engagement with each of said flanges.

4. A partition construction as stated in claim 1, wherein in said ceiling runner is of U section, has a width corresponding to the thickness of the core panels, and is provided with bendable tabs at the walls of the U-section grasping the upper edge portions of core panels to prevent lateral movement thereof.

5. In a readily assembled, demountable, self-contained, non-load-bearing partition construction adjustable to different thicknesses of partition walls, the provision of: an adjustable floor runner comprising a pair of metallic members, each provided with a vertical, longitudinally extending web, one of said members having a foot plate extending laterally in both directions, and a top plate extending laterally in a direction away from the other member, the other of said members having a foot plate extending in a direction away from said one member and a top plate extending in the same direction, whereby said second member is positioned on the foot plate of the first member with the webs of said members in desired spaced relation; means carried by foot plates of each of said members connecting said members together with their webs in desired spaced relation; and upstanding flanges carried by the outer edges of each of said top plates.

6. In a readily assembled, demountable, self-contained, non-load-bearing partition construction adjustable to different thicknesses of partition walls, the provision of: an adjustable floor runner comprising a pair of metallic members, each provided with a vertical, longitudinally extending web, one of said members having a foot plate extending laterally in both directions, and a top plate extending laterally in a direction away from the other member, the other of said members having a foot plate extending in a direction away from said one member and a top plate extending in the same direction, whereby said second member is positioned on the foot plate of the first member with the webs of said members in desired spaced relation; providing a core panel receiving space; means carried by foot plates of each of said members connecting said members together with their webs in desired spaced relation; upstanding flanges carried by the outer edges of each of said top plates; a laminated core panel positioned between the vertical webs of said members and within said receiving space and grasped thereby; and surface panels adhesively secured to the external surfaces of said core, bottom edges of said surface panels resting upon said top plates.

7. In a partition construction of the character stated in claim 5, the provision of upstanding flanges carried by an outer edge of each of the foot plates and a removable kick plate carried by each of said members, said kick plate cooperatively engaging and extending between the flanges on the foot plate and top plate of its respective member.

8. In a non-load-bearing partition construction, the combination of: a longitudinally extending, laterally telescoping floor runner means anchored to a floor, said floor runner means including interconnectable companion bottom plates, vertical webs and top plates provided with upstanding flanges along longitudinal edges, and means for adjustably connecting said bottom plates for spacing said webs for receiving varying thicknesses of partition

walls therebetween; a ceiling anchor in alignment with said floor runner means, said ceiling anchor including means adapted to restrain lateral movement of a core panel in one direction; core panels, each composed of a plurality of pre-secured, fabricated boards in face-to-face relation, supported by said floor runner means and extending into contact with said means to restrain lateral movement in one direction; means associated with a ceiling and adapted to engage upper edge portions of said core panels to restrain lateral movement thereof in the opposite direction, said core panels having their vertical edges in abutting relation; and surfacing panels adhesively secured to external surfaces of said core panels, upper edge portions of said surfacing panels extending above the tops of said core panels and enclosing the ceiling anchor means, vertical edges of said surfacing panels being displaced longitudinally with respect to the vertical edges of said core panels, the lower edges of said surfacing panels being restrained from lateral movement by the upstanding flanges of said floor runner means.

9. In a readily assembled, self-contained, non-load-bearing partition construction adjustable to different thicknesses of partition walls, the provision of: an adjustable floor runner comprising a pair of members, each provided with a vertical, longitudinally extending web spaced from the web of the other member to provide a core panel receiving space; each member having a foot plate and top plate extending laterally outwardly from its web in a

5
10
15
20
25

direction away from the other member, each of said top plates providing a supporting surface for bottom edges of surface panels which together with the core panel form the partition wall; means carried by the members connecting them together with their webs in desired spaced relation; upstanding flanges carried by outer edges of the foot plates; upstanding flanges carried by the outer edges of the top plates; and a removable kick plate cooperatively engaging and extending between said flanges on the foot and top plates of its respective member.
